FLYING CRAFT

Application filed July 5, 1929. Serial No. 375,916.

Our invention relates to a flying craft. It pertains more particularly to that type of craft known as the rigid, lighter than air ship.

5 It is generally recognized in the art that a rigid craft employing the gas buoyancy principle exemplifies the ideal economic mode of air transportation. Past and present day experiments have proven these 10 facts. However, there has been considerable criticism of this type of air craft, owing to its inability to travel between relatively remote points with adequate speed and endurance. Structures previously used have 15 apparently tended to set up adverse air packs and air currents which served to materially retard the forward motion of the craft and even to subject it to strains and wrenches sufficiently severe to completely 20 disable the ship.

One of the objects of our invention is to provide a lighter than air craft employing the principle of gas buoyancy in combination with a structural design suitable for 25 speed, endurance, and a great load capacity.

Another object of our invention is to provide rigid lighter than air craft with power mechanism which bears an improved relation, from a standpoint of position, to the 30 center line of resistance to travel of the air ship.

Still another object of our invention lies in the provision of a lighter than air craft capable of being adequately controlled by 35 means of stabilizers, elevators and rudders of a smaller size than those previously considered necessary.

Another object of our invention is to provide a rigid lighter than air craft so constructed that the forward movement thereof through the air will not be retarded by the resistances which have previously been set up against the travel of previously known 40 air craft of this type.

45 Another object of our invention lies in the provision of a cabin for our airship that is disposed on the longitudinal lower center line of our craft, forming an integral portion of the hull, and acting as a stabilizing keel therefor.

It will be understood, as this description progresses, that certain features of our invention are not necessarily limited strictly to the type of flying craft shown but may be capable of use with other types of craft. 55

Our invention contemplates the provision of a rigid lighter than air craft whose general contour is such that the tendency to the formation of vacuum pockets and eddies of air about the ship will be materially diminished. In conjunction with this, the power mechanism utilized is of such form and so disposed that the air currents created by the passage of the ship through the air will be positively controlled in such a way as to further dissipate these undesirable vacuum pockets and eddies of air. 60 65

More specifically, our invention preferably comprises a rigid, lighter than air craft wherein the main body of the craft is of cylindrical form with its longitudinal side lines straight throughout the greater portions of the length of the ship. Furthermore, the ship is preferably so constructed that it is provided with a nose shaped to cut the air and direct it into corridors which are disposed longitudinally of the ship on the sides thereof and which are provided with motor driven propellers located within these corridors and serving to draw the air displaced from the 70 front of the ship into these corridors and along the same. 75 80

The corridors are preferably provided with side openings which avoid the danger of packing the air in the corridors and which furthermore serve to permit the propellers and the windstream created thereby, in the corridors to draw the air adjacent the outside of the corridors into a space between the propeller tips and the walls thereof, with a subsequent dissipation of any vacuum pockets or undesirable eddies that might otherwise be set up around the sides of the ship. 85 90

These corridors preferably extend entirely through the ship from points adjacent the nose thereof to points adjacent the rear end thereof and the air is positively drawn through these corridors and expelled through their rear ends. The expulsion of the air 95 from the rear ends of the corridors is effected 100

under pressure. Being discharged in this manner, it is caused to follow the stream line design of the tail, thus destroying any air pockets and vacuum sucks in rear of the tail, and in addition joining the air coming over the longitudinal sides of the craft in such a manner that a pinching effect around the tail is produced.

The corridors and, consequently, the propellers preferably coincide substantially with the center line of resistance. Furthermore, the stabilizers, elevators and rudders of our preferred type of ship are in direct line with the slip stream of the propellers, obviating any danger of a rarefied atmospheric condition around these parts and ensuring that the ship will respond quickly to its control and thereby ensuring easier handling under all conditions of operation.

There are numerous other features of our invention which constitute important advances in the art. These will be set forth as this description progresses.

Other objects and novel features of our invention will be noted in the following detailed description and one embodiment thereof will be shown in the accompanying drawings wherein like characters of reference designate like parts and wherein:

Figure 1 is a perspective view, partly in section, of our airship.

Figure 2 is a side elevation, partly broken away, showing various elements of our craft.

Figure 3 is a cross sectional view taken on the line 3—3 of Figure 2.

Figure 4 is a front elevation of our aircraft.

Figure 5 is a cross sectional view, partly broken away, taken on the line 5—5 of Figure 2.

Figure 6 is a perspective view of the tail section of our craft.

With reference to the drawings, we have shown therein one embodiment of our air craft as comprising a substantially cylindrical or tubular main body portion 1, that is circular in cross section as shown in Figure 4. This main body portion 1 may be oval if desired, although we have preferably shown it circular.

The longitudinal sides of the main body 1 extend in a straight line so that this body is cylindrical rather than cigar-shaped. They are provided at the forward end with a nose section 2 formed integrally therewith and as a part thereof. The main body is further provided at the tail end with a tail section 3 formed integrally therewith and as a part thereof.

The upper and lower longitudinal center lines of the craft extend in a straight line from fore to aft and terminate at the nose 2 in a vertical knife-edge prow member 4 and at the tail section 3 in a vertical rudder post 5.

The sides of the craft in addition to those of the upper and lower center line extend in straight lines longitudinally intermediate the rudder post 5 and the prow 4 and are of such length and position as to form the arcuate inner confines of the nose section 2 and tail section 3 respectively, as will be hereinafter noted.

The nose section 2 which comprises an integral portion of the body 1 is provided at the forward end thereof with the vertical knife-edge prow member 4, Figure 1, which is preferably disposed intermediate the girders forming the upper and lower longitudinal center lines. The sides of this nose section each take the general form of a funnel open at one side and having its outlet orifice concentric with and merging into side corridors formed in the body portion of the craft. The funnel-like curvature of each side of the nose, Figure 4 or 1, is slight in that area designated by the numeral 6. It becomes more pronounced in that area designated by the numeral 7, so that it assumes a substantially circular contour merging with the forward end of a longitudinally extending circular corridor 8, one of which is formed in the side of the body 1.

The prow member 2 is of very slight width and serves to separate the air into two streams. Then, the funnel-like sides of the nose receive and direct the two streams of air into the corridors 8. Thus, the air is both split and controlled and finally directed to points where it is converted to advantageous rather than to detrimental uses, in a manner that will be made more clear as this description progresses.

Stating the matter in a somewhat more technical way, each side of the nose has a surface which is curved in the direction of length of the ship and which is also curved in a direction at right angles to the length of the ship. This produces a compound curved surface which receives and conducts the air with a minimum amount of resistance into the corridor at the inner end of the surfaces. The prow member 2 is shown as being equipped with a ring member 10. This member may be used as a securing element for holding the craft to a mooring post or tower. The nose section of the craft is fitted in between the upper and lower surfaces of the main body portion, the straight line longitudinals having been progressively decreased to give the proper outline thereto. This nose section may be formed of a light metal such as aluminum or the like.

The two longitudinally extending circular corridors 8, hereinbefore mentioned, are disposed on either side of the craft in direct alignment with each other and with the horizontal center line of the craft. Thus an imaginary line passing transversely through the diametrical center of each corridor would

also bisect the horizontal center of the main body 1.

The diameter of these corridors 8 is preferably slightly more than the diameter of the 5 propeller blades 11 mounted on the motors 43 disposed within the corridors which will be hereinafter referred to.

It will be noted in Figure 2 that one of the 10 corridors 8, shown therein, extends longitudinally of the main body 1 and is in communication, at the front end, with the funnel-like portion 7 of the nose surface 2, both funnel-like surface and corridor being of equal diameter at that point. The after end of the 15 corridor 8 is similarly in communication with a funnel-like area of the tail surface 3. The corridor 8, is further provided with a side open to the atmosphere as at 12 that extends throughout its length. The function of this 20 open side will be hereinafter referred to.

The tail section of the craft is shown best in Figures 2, 5 and 6. It is fitted in between the upper and lower surfaces of the main body portion. In between these upper and 25 lower surfaces, each vertical surface of the tail section embodies a flaring concave portion 13 which is, in reality, a widened continuation of the rear end of the corridor 8. This flaring concave portion 13, however, merges into 30 a convex stern portion 14 terminating in the stern post 5.

The structure just described is preferably produced by progressively decreasing the 35 length of the straight line longitudinals of the body portion to give the proper outline of the tail section as described, when the light metal covering is interposed intermediate the straight line upper and lower surfaces.

The stabilizers 15 are mounted on the tail 40 end surface 3 directly in line with the corridors 8 and extend outwardly from the body of the ship. They are provided with the elevators 15' attached to the rear end thereof. Suitable operating mechanism as at 47 may 45 be mounted in connection with the elevators and suitable control wires may be conducted forward through the main body 1 in any manner desired to the control cabin hereinafter referred to.

50 The stabilizers are placed on opposing faces of the tail end 3 and are disposed in direct horizontal alignment with the horizontal diametrical center of the corridors 8 and the horizontal center line of the craft.

55 The rudder post 5 is equipped with a vertical rudder 16 that is preferably of the rectangular proportions shown and of the same height as the distance between the upper and lower center lines of the craft.

60 Suitable operating mechanism comprising wires and other common known means of control as at 48, Fig. 1, may be provided for swinging the rudder from one side to the other about its pivotal connection with 65 the rudder post 5. The control wires there-

fore are also conducted forward through the main body 1 to the control cabin.

If desired, an electrical control can be interposed intermediate the control cabin and the elevators and rudders, and by proper energization can be operated to automatically 70 control the ship.

The methods of controlling the elevators and stabilizers are well known to those versed in the art, and it is our desire to utilize any 75 common known mechanisms for operating these members.

The craft is further provided with a cabin 17, Figure 2, that is formed integrally with the framework and extends below the ship. 80 The cabin is so constructed that the longitudinal center thereof is in direct alignment with the longitudinal center of the craft.

This cabin preferably extends under that section of the craft wherein the lifting cells 85 are disposed. It will be noted in Figure 2 that it is of about the same length as the corridors 8, although the cabin may be of any length desired and of any design. The rear-most end of the cabin as at 18 curves upwardly toward the underside of the hull 1. 90 This is primarily to relieve wind resistance or to eliminate the air suck that would normally be created by a square end cabin. The forward end may be similarly curved, if 95 desired.

The control room is adapted to be partitioned off from the balance of the cabin and will form the foremost part thereof. It will be provided with the usual means for controlling the craft; and in addition will be provided with transparent panels wherever desired to allow the greatest possible vision to the navigators. In rear of the control 100 room the cabin will be divided into the various other rooms suitable for crew quarters, 105 passenger staterooms, etc.

The position and the rigid connection of the cabin to the ship is such that it may be utilized as a keel therefor. This is extremely advantageous in that the cabin forms an integral part of the framework, as will be hereinafter related, and all of the weight 110 thereof is disposed on the lower longitudinal center line thus tending to steady and balance 115 the ship.

The numeral 19 designates a plurality of propeller operated generators that are disposed on the underneath side of the cabin 17 and depend therebelow, being automatically 120 operated as the craft travels forward. Furthermore, these generators are positioned along the horizontal center line of the cabin, as shown in Figure 3. The function of these generators is to provide the power necessary for heat, light, and radio purposes and they may be provided with suitable means for drawing them into the cabin proper when not in use.

The supporting framework for each gener- 130

ator 19 preferably comprises a forked member such as shown at 20, Figure 3, which is bolted or otherwise secured to one of a plurality of transverse floor beams 21. These transverse floor beams are disposed in spaced relation throughout the length of the cabin 17 and are supported by means of the vertical uprights 22, which are riveted or otherwise secured to one of a plurality of transverse overhead beams 23. It can be seen in the drawings that the uprights 22 may be used as a means for partitioning the cabin proper into the various rooms and compartments common to craft of this type, by merely placing cork board or other light material therebetween.

The girders 23 are positioned transversely throughout the length of the cabin and are supported by means of the cross braces 24 or other suitable means that depend from one of a plurality of second transverse girders 25 disposed directly above the girders 23. The space intermediate the girders 23 and 25 may be utilized, adjacent each outer side, as at 26, for the storing of gas, oil or other articles. The inner surface, not taken up by the hull longitudinals of the craft, may be utilized as a conduit for the various control wires. A suitable outside covering as at 27 may be mounted on the cabin framework just described, wherein windows, doors and port holes may be placed.

This covering is preferably a light metal such as duralium and is adapted to be mounted on the cabin framework in such a manner that the angling vertical sides, 27 thereof may be secured longitudinally adjacent the sides of the ship to one or more of the longitudinals 31, thus aiding in the support of the cabin and also forming a weather tight contact.

The girders 25 are disposed in spaced relation throughout the total length of the craft, being foreshortened transversely as at 51 (Figure 5) near the tail and nose sections to accommodate for the reduction in cross sectional areas at those points (see Figure 5). They are arranged transversely of the craft and are further provided with the longitudinals 50 that comprise the floor section of the main transverse section, hereinafter referred to, that extend longitudinally of the craft (Figure 5) and are successively terminated in accordance with the lines of the tail and nose, thus making it possible to secure them adjacent the nose and tail sections on one or the other of a plurality of the girders 25 (Figure 5).

The structure thus formed by the union of the longitudinals 50 with the transverse girders 25 might be called a floor section of the hull. This floor section lies horizontal with relation to the vertical center line of the craft and is adapted to support the balloonettes 29 and gas cells 28 hereinafter referred to.

In Figure 1 we have shown the actual construction of the hull which comprises a plurality of longitudinals 31, extending longitudinally of the craft that are arranged circumferentially around and supported on a plurality of ring members 30 and 30'. Each longitudinal preferably comprises three elongated bars that are riveted or otherwise secured together to form a hollow triangular member, the base of which is positioned on the members 30 and 30'.

Each ring member 30 and 30' is arranged in such a manner from fore to aft to give adequate support to the longitudinals which are arranged thereon in spaced relation and entirely therearound. Some of the ring members 30, form a part of the main transverse sections hereinafter referred to, while other ring members as at 30', are positioned intermediate the members 30.

The ring members 30 and 30' each form a complete circle and a section of each member lies in that area intermediate the transverse girders 23 and 25. Some of the longitudinals 31, also normally lie in the space intermediate the transverse girders 23 and 25. If desired the transverse girders 23 may be secured to the longitudinals connecting therewith as at 52 and 53 to aid in the support of the cabin 17.

We have now provided a hull for our craft comprising spaced longitudinals 31 arranged circumferentially around a plurality of ring members, and a floor interposed in the base of the hull comprising the horizontal transverse sections 25 and the floor longitudinals 50.

It will be noted in Figure 3 that the two upper longitudinals 32 and 33 and the two lower longitudinals 52 and 53 are arranged on either side of the upper and lower longitudinal center line; otherwise the disposition of the girders would be such that the two opposite side center line longitudinals would cover the corridor openings 12.

It will be understood that this craft will be divided into a plurality of cell sections, as shown in Figure 1 or 5, each section being identical in construction, although of lesser area at the tail and nose, owing to the reduction in cross sectional area at those points.

In dividing the craft into sections, each of which is adapted to be provided with a gas cell 28 and a balloonette 29 hereinafter referred to, we have provided a plurality of main transverse sections that are disposed throughout the body of the craft at spaced intervals. These sections at the fore and aft, are of necessity of lesser dimensions but are constructed in an identical manner with those in the body 1 of the craft.

These main transverse sections preferably comprise a plurality of radials 34 that are secured at one end to a center ring member 35 and extend radially outwardly therefrom.

each separate radial 34 being secured at the other end to a longitudinal 31.

The center ring 35 is disposed on the longitudinal center line of the ship, and various 5 wires, struts and cross braces (not shown) may be interposed between the ring member 35 and the longitudinals to aid in maintaining the stability of the sections.

In Figure 5, it can be seen that some of 10 these gas bag sections are of necessity of somewhat lesser area, especially at the rear end of the ship wherein the convex outer tail portion makes it necessary to somewhat reduce the 15 contour of the ship at this point. The foremost gas bag section is somewhat reduced in area adjacent the front part thereof.

The center ring member 35 is to be found 20 joining each set of radial bars 34 which form the confining wall of a plurality of gas cell 25 sections. Each ring member 35 is disposed on the longitudinal center line of the craft and is adapted to support a tubular member 36 extending longitudinally of the craft from fore to aft. Within this tubular member 36 a 30 steel cable extends from the rudder post 5 to the knife edge prow 4. It is secured to both of these members by rivets, bolts or other well-known means. The purpose of this steel 35 cable is primarily for providing a means for preventing the gas cells from moving laterally and is well known to those versed in the art.

The gas bags 28, which are circular in cross 40 section are provided with vertical sides, as shown in Figure 1, and are further provided with a centrally disposed longitudinally extending opening through which the tubular member 36 extends. The bag is so constructed that the buoyant gas held therein will not 45 leak or escape around this central opening.

Each gas cell section is provided with the 50 gas cell 28 and a balloonette 29 that is disposed directly below the gas cell. This balloonette 29 is of an oval tubular shape when 55 distended. This member is for the purpose of preventing the gas cell from sagging when the gas therein becomes somewhat rarefied and contracts thus allowing the sides of the 60 cells proper to lose their shape and to fall away from the hull of the craft. To remedy this condition the balloonette is merely inflated which, as shown in Figure 3, will press 65 upwardly against the base of the cell proper thus compensating for any sag produced in the cell by a rarefied gas condition.

We have preferably provided each balloonette 70 with a separate valve member, (not shown) that is connected to a fluid source of supply. Inasmuch as each balloonette is disposed beneath a separate gas cell, it will be 75 possible to inflate or deflate each balloonette separately. The material used in the construction of the gas cell and balloonette may 80 be of any type desired.

65 It will be noted, in Figure 1, that each cell

is provided with the customary gas cloth outer covering 37. This covering is preferably made of a strong light fabric, and is disposed around each cell and lies intermediate the outer surface of the cell proper and a 70 steel wire mesh 38. When the gas cell is fully inflated, the gas cloth 37 prevents the cell cloth from chafing against the wire mesh which in turn restrains the cell from bulging or coming out of shape and lies adjacent the 75 inner surface of the longitudinals, being pressed thereagainst during inflation of the gas cells.

It will be noted in Figure 3 that the gas 80 cell 28 shown therein, folds without kinking around a longitudinally extending section reserved for the corridors 8.

These corridors 8, which are preferably constructed of a light metal secured to the proper framework, extend well into the body of the ship. To make it possible to provide a plurality of corridors 8 it has been necessary to somewhat alter and strengthen the framework at that point. It must be remembered that the corridors are provided with longitudinal 85 openings that are positioned along the outside of the craft.

In accomplishing this, we have allowed the ring members 30, both the ones that are secured to the radial bars making up the main transverse frames and the auxiliary members 30' encircling the frame intermediate the main transverse sections to extend without a break totally around the hull.

The ring members 30 are properly reinforced owing to the fact that they aid in the support of the main transverse sections. The circular members 30' are merely binders, (Figure 1).

At a point above the actual corridor area, the longitudinals 31 are provided with an inwardly extending downwardly angling section as at 40, (Figure 3) to which is secured a plurality of auxiliary longitudinals 41. These longitudinals 41 are maintained with in the ship and are secured preferably at either end on one of the end main transverse sections that lie adjacent thereto.

It can be seen from the drawing that the member 41 and the longitudinals are spaced and braced horizontally and vertically in such a manner that a sheathing of light metal may be mounted therein in such a manner as to present a cylindrical tubular surface converging at either end, with the nose and tail surfaces.

At the juncture of the main transverse partitions with the corridor structure, the ring member 30 is of a somewhat strengthened 125 nature and is built to uphold a motor 43. Not all of the main transverse partitions adjacent the corridors are provided with motors, but they are so constructed and of sufficient strength that the proper elements for 130

supporting a motor could be placed therein and a motor mounted if desired.

In mounting the motor, a plurality of radial arms 42, of heavy construction are rigidly, or resiliently, if desired, secured to the adjacent framework of the corridor wall. The motor 43 is interposed at the juncture of these arms 42, thus spacing and bracing the motor both horizontally or vertically.

10. It is desired that the motor be so positioned that the propeller arc will not extend beyond the ring member 30. The exterior of the ship is preferably covered with a material suitable to craft of this type. The nose and tail sections are preferably covered with a light metal which would be more adequate for 15. withstanding the pressures and elements without a resilient action as found in a yieldable cloth that might be detrimental to their particular functions.

In addition, we have shown in Figure 2, a water ballast system comprising a forward tank 44 and a rear tank 45 connected by a pipeline 46 extending longitudinally of the 25. craft and conducted through the transverse girders 23. When it is desirable to elevate the nose of the ship, irrespective of the elevator tilt the fluid means may be forced by pressure back into the rear tank thus shifting 30. the weight of the fluid so as to lower the rear end.

In the operation of this air ship it will be best to bear in mind that when the propellers are operating the air in front of the ship is 35. drawn over the nose and driven through the corridors on either side thus reducing the head resistance to a minimum.

It is a feature of this air craft to have the forward propellers rotating in a clockwise 40. direction. It can be seen in Figure 5 that a column of air of approximately the same diameter as the propeller, will be moving longitudinally through the corridor 8 and will be whirling (at a high velocity) in the direction 45. of the arrows. The middle propeller, which is disposed intermediate the forward and rear propeller, is adapted to be rotated in the opposite direction to that of the forward propeller. It can readily be seen that the column 50. of air coming from the forward propeller will be whirling in one direction and the propeller blade of the second motor will be rotating in opposition thereto. If the second 55. propeller and the column of air in front of it were rotating in the same direction, the motor would have little or no work to do owing to the fact that it would merely be boosting this air column in its original circular path of 60. travel.

By reversing this propeller arc it is found that the propeller will have to do work to reverse the whirling action of the column of air coming from the forward propeller.

65. In this manner we have made the center pro-

peller effective whereas it would normally be nothing more than an idler.

The rearmost propeller is adapted to be rotated in the same direction as the forward propeller or, in opposition to the center propeller. The air column coming from the center propeller will be traveling in a reverse spiral to the direction of rotation of the rear propeller. Here again we have provided a column of air whirling in one direction and a propeller whirling in another direction that, as a result, will cause the rear propeller to do work on the column of air to reverse its whirling path of travel.

By referring to Figure 5 it can be seen that the column of air coming from the rear propeller will be blasted rearwardly along the stream line hull of the tail section. The stabilizers 15, due to their advantageous position, are maintained directly in the center of this diverging column of air coming from the rear propeller. It can readily be seen that the velocity of this air will render the elevators 15' and the rudder 16 highly effective even if there are adverse air currents blowing thereagainst or even if the air through which the craft is passing is not in motion.

It is well-known that a column of air such as that created by the propellers and moving through the corridors will more or less be traveling at a high rate of speed and furthermore will remain, up to a certain point, at a constant diameter. It has been hereinbefore revealed that the propeller diameter is slightly less than the diameter of the corridor. It can readily be seen that the column of air moving rearwardly through the corridors would remain at a diameter equal to that of the propeller blade. Thus between the outer periphery of this moving column of air and the inner surface of the corridors there will be a layer of air that will be affected by this moving column of air. As the velocity of this moving column of air is increased, this layer of air will tend to move in the same direction, only with lesser velocity, than the moving column. This action will cause the air surrounding the ship and especially the air adjacent the longitudinally extending side opening of the corridors to be drawn into the space intermediate the moving column of air and the inner side of the corridor wall. This air is carried along by the moving column of air from the propeller and is eventually exhausted at the rear of the ship. The action of the circular column of air on this second layer of air might readily be termed a siphoning action.

By pulling the air adjacent the longitudinal side openings of the corridor thereinto, it can be seen that any eddy or swirl of air set up by adverse air currents will be pulled into the corridors.

Again referring to the nose of our air

craft it will be noted that the action, of the two forward propellers, will tend to create a rarified atmospheric condition, not only adjacent the actual nose surface, but in addition 5 will positively act on the air lying within an area equal to approximately three to four times the diameter of the propeller. This action of the propellers is sufficient to break down any resistance, or to disperse any air 10 pack that might be formed at the nose of the ship.

It has been hereinbefore mentioned that the longitudinal sides of our air craft are maintained in straight line, the upper and 15 lower center lines thereof extending from fore to aft. A feature of our invention lies in the fact that these straight longitudinal sides effectively relieve eddies and vacuum pockets around the body and over the tail of 20 the ship. It might even be said that this even flow of air aided by the volume of air traveling at a high velocity being vented from the rear propellers will materially aid in causing 25 the air flowing along the sides of the ship to be drawn down and around the convex rear end, thus eliminating any vacuum suck and creating a pinching effect therearound (see arrows Fig. 1).

It can readily be seen that a craft designed 30 along the line hereinbefore set forth, will unmistakably have a free passage through its supporting fluid. The nose of our craft is capable of parting the air and causing it to flow evenly and smoothly over the longitudinal 35 sides of the craft, and in addition to be driven through the corridors in such a manner that the easy reunion of the molecules of air originally separated at the nose, is made possible. The column of air venting from 40 the corridors and that flowing from the sides of the ship will come together at the tail end without clashing or setting up disturbing eddies that might result in a vacuum suck 45 normally found in craft of the regulation type.

We have paid particular attention to the disposition of the corridors and the motors mounted therein. By positioning these corridors, in the manner shown, we have made 50 it possible to apply the motivating power on the center line of resistance, thus reducing the actual amount of power needed to move the ship, through the air, to a minimum. Some 55 direct advantages of this construction lies in the fact that smaller motors may be utilized thus decreasing the fuel load necessary to operate them.

It will be obvious that there are numerous 60 other advantages arising from the various novel features outlined. These will appear to some extent from the claims of this application.

Having thus described our invention what 65 we claim is:

1. In a rigid aircraft, a plurality of pro-

pelling elements disposed in corridors extending longitudinally of said craft, each corridor having side openings extending longitudinally the length thereof, said propelling elements operating to first create a 70 column of air in said corridors traveling in one direction, that will be first whirled in one direction, then in another.

2. In a rigid aircraft, a plurality of propelling elements disposed in corridors extending longitudinally of said craft, each corridor having side openings extending longitudinally the length thereof, said propelling elements operating to first create a 75 column of air in said corridors traveling in one direction, that will be first whirled in one direction, then in another, said moving column of air capable of drawing the air from the sides of the ship adjacent the corridors 80 into the corridors.

3. A rigid lighter than air craft comprising a body portion having longitudinal corridors substantially throughout the length thereof, said corridors having side openings 85 extending throughout the length thereof, and propellers for forcing air through said corridors and delivering it under pressure over the exterior tail surface of the craft and in contact with the rudder and elevators.

4. A rigid lighter than air craft comprising a body portion having longitudinal corridors substantially throughout the length thereof, a wedge-like nose with its sides converging into said corridors, said sides being 90 of funnel-like formation, propellers in said corridors, the rear ends of said corridors being so disposed as to deliver air under pressure around the tail of the craft.

5. In a flying craft, a housing therefor, 100 said housing having a nose portion, comprising a vertical prow, concave surfaces disposed on either side and in rear of said prow, said concave surfaces forming a funnel like surface adjacent the foremost ends of a plurality of longitudinal corridors, said corridors disposed in alignment with the longitudinal centerline of said craft, and extending throughout the length of said craft, being in communication, at the rear end, with a flaring inwardly converging tail surface, 110 said tail surface being substantially funnel shaped adjacent the rearmost ends of said corridors, motors disposed in said corridors, said motors capable of creating a rarefied atmospheric condition adjacent said nose of 115 said craft and capable of drawing said air into the corridors, said air being vented at the tail of said ship over and around the elevators, stabilizers and rudder disposed on the tail section in the direct path of said vented air.

6. In a rigid lighter than air craft, a housing therefor having substantially straight lines longitudinally, a plurality of corridors 120 extending longitudinally of said housing 125

130

and having side openings therein extending the entire length of said corridor, a cabin formed as an integral part of said housing and extending therebelow, said cabin being disposed on the lower longitudinal centerline of said housing, said cabin forming the keel of said craft.

7. In a rigid lighter than air craft, a tail surface comprising funnel-like surfaces in communication with, at their smallest ends, the ends of a plurality of longitudinally extending corridors, said funnel-like tail surfaces converging inwardly toward each other and toward a vertical tail post, said funnel-like surfaces having a substantially vertical surface adjacent said vertical tail post.

8. In a rigid lighter than air craft the combination of a nose having substantially funnel-like surfaces in communication with a plurality of longitudinally extending corridors and a tail having substantially funnel-like surfaces in communication with the other end of said longitudinally extending corridors.

In testimony whereof we hereby affix our signatures.

JESSE E. LESH.
JOSEPH W. HOHL.
